VENTILATOR, AIR DIFFUSER, AND THE
LIKENorman Finlay Johnston, Glasgow, Scotland, as-
signor of one-half to John Marshall, Glasgow,
ScotlandApplication May 3, 1938, Serial No. 205,826
In Great Britain April 10, 1937

4 Claims. (Cl. 98—40)

This invention relates to ventilators, air diffusers and the like, and more particularly of the ball and socket type for controlling the air passing through the ventilator or diffuser into a room, cabin or the like, and the direction thereof. In such devices, the ball is generally provided with a mouth-piece or flared opening which projects from the ball and is capable of being moved about in its socket or mounting to control the direction 5 of the stream of air discharged. In such a device, however, the mouth-piece must be placed in one position where the stream of air will be completely cut off by a valve fixed on the back of the mounting which obturates the inner orifice in the ball member, and therefore in this position there 10 is a considerable area covered by the mouth-piece, over which air cannot be discharged.

The object of the invention is to improve this type of controlling means, whereby the stream 20 of air may be discharged in all directions and the valve may be eliminated.

The invention is hereinafter described by way of example with reference to the accompanying drawings, in which:

25 Figure 1 is a sectional elevation of a ventilating device.

Figure 2 is an inverted plan of Figure 1.

Figure 3 is a sectional elevation of a modification of the device as shown in Figure 1.

30 Figure 4 is an inverted plan of Figure 3.

Figure 5 is a sectional elevation of a modification of the device shown in Figure 4.

Figure 6 is a side elevation of Figure 5 in section.

35 Figure 7 is a sectional elevation of another form of the device.

Figure 8 is a plan of Figure 7.

In carrying the invention into effect, according to the form shown in Figures 1 and 2, by way of example, the controlling means is fitted to an ordinary air inlet duct 1, such as is used in the cabin of a ship and comprises a socket 2 formed as a spider located in the mouth of the duct, which has two ribs or arms 3 which provide a spherical interior. The socket terminates just short of the line A A drawn through the centre C of the sphere. Three or more ribs may be employed instead of two. In this spherical socket 2 is mounted a sphere or ball member 4 which is held therein by means of a cover or locating plate 5, the inner surface of which is cylindrical between the line A A and the socket 2 and spherical for the remainder of just sufficient depth so that it encloses more than half the ball member 4, thereby preventing it from falling

out of the socket 2. Instead of making the joint between the socket and the cover plate offset from the line A A it may be made on the line A A or on the other side of the line A A to that shown in Figure 1.

The ball member 4 is made solid and two circular apertures or holes 6, 7 are provided in the ball member and meet in the interior to form a passage 8 therethrough. The two apertures are situated within the area of the ball member enclosed by the mounting which is formed by the socket and the locating plate. In other words the two apertures 6 and 7 are outside a spherical segment which will close the passage when the ball member is rotated to the closed position. The 15 spherical segment must, therefore, have a diameter at least equal to the smallest diameter of the opening. If desired, this passage leading from one aperture to the other may be made by drilling two holes substantially at right angles or at any other angle which meet in the centre of the sphere, and thereby make an elbow shape passage from one to the other, or any other suitably shaped or directed passage between the two 20 may be employed.

25 On the surface of the ball member remote from the two apertures, a projection or knob 10 is provided, whereby the ball member may be moved so that the two apertures are contained wholly within the socket and covered, as shown in dotted lines in Figure 1, in which position the device is closed and the spherical segment then closes the opening in the socket. This knob is also used for opening the device and moving the apertures so that they will allow a stream of air to pass 30 into the said cabin in a variable direction.

When one of the apertures is within the socket and the other aperture without, the ball member can be moved by placing the finger on the knob and moving the exposed aperture round to any 40 position whereby a stream of air can be directed over the whole area of the cabin or the like.

If desired, the ball member may be made hollow with a shell of uniform thickness and soft material 45 9 may be placed between the arms 3 and the ball member 4 so that it is held firmly but at the same time is permitted to be moved easily by the knob 10. In order to give a more uniform direction of air a deflector 11 may be situated within the passage 8 in the ball member 4.

50 Instead of having a knob 10, several dimples or dents 12 may be provided in the surface of the ball member 4, as shown in Figure 3. When thus provided the ball member may also be turned so that both the apertures are exposed and not con- 55

tained in the socket, and in this position also the device will be closed and no air will be permitted to enter the cabin or the like.

It is found in practice, however, that the ball member tends to turn round so that the plane containing the centre line or longitudinal axis of the passages deviates from being at right angles to the socket or mounting, and to overcome this difficulty the ball member is preferably provided with two trunnion pins 13, as shown in Figures 3 and 4, and the mounting is formed by an annular socket ring 14 and a cover ring 15 having an annular recess or groove 16 formed between the two into which a trunnion bearing ring 17 is located to rotate freely and supports the pins 13 in suitable bearings. Instead of mounting the pins 13 in the trunnion ring they may be housed freely in the recess or groove 16 or the pins 13 may be provided with bushes forming trunnion bearings which can slide freely in the groove 16. Further, instead of having a complete trunnion ring 17 two portions of ring of any suitable articulate length forming trunnion pieces or bearings 17 may be employed, as shown in Figure 4. The trunnion ring or trunnion pieces distribute the pressure of the pins and prevent the thin portion of material of the ring 15 over the groove 16 being broken away, should any strain be put upon the ball.

30 The fitting of trunnion pins prevents the ball from being moved so that the plane containing the centre line or longitudinal axis of the passage 8 deviates from being at right angles to the socket or mounting. Further, the pins also have the advantage of preventing the ball from being pulled out of its socket or mounting.

It will be noticed that in Figure 3 the apertures 6 and 7 forming the inlet and outlet of the passage 8 are situated wholly within one hemisphere of the ball member. By this arrangement the passage 8 can be swung about an axis which is preferably horizontal and this axis is itself capable of being rotated about an axis at right angles thereto, which is preferably vertical; consequently, the outlet 7 can be moved to deliver air in any direction.

It is to be understood that the socket or mounting may be situated in a horizontal, vertical or any other plane.

50 According to a further modification, as shown in Figures 5 and 6, the surface of the ball member between the two apertures may be removed, whereby a slot is formed which will permit the air to pass more freely from the duct 1 out into the cabin. When the sphere is hollow, just the wall of the sphere is removed between the two apertures, but when the sphere is solid, then all the material between the two apertures is removed so that there is a slot which is bounded by the 55 wall of the passage and the slot extends from one aperture to the other and right into the interior of the sphere. One deflector 11 is shown, but any other number, as shown in dotted lines, may be added to suit requirements.

65 In accordance with a further form of the invention, as shown in Figures 7 and 8, the ball member and socket instead of being mounted directly on the mouth of the air duct 1 is mounted in the centre of an air diffuser, having, for example, concentric vanes or louvres. The socket is formed by the three ribs or arms 3 secured to the cylindrical member 19 and the ball member 4 is held therein by a ring 20, a portion of the interior of which is spherical. The ring 20 forms 70 one of the vanes or louvres and is secured in

common with the others to the three arms 21, which are all secured to the foundation 22 mounted upon the end of the duct 1. If desired, the ball member may be provided with trunnion pins 13 which are mounted in a trunnion ring 17 located in a recess 16, as shown in Figures 3 and 4. By mounting the controlling means in the centre of the diffuser, a directional stream of air may be discharged in any desired direction, in addition to the diffused air which passes through 10 the said louvres or vanes. If not required, the ball is turned so that the centre is completely closed, and then no directional stream is obtained, but only the diffused air from the vanes or the like.

When the ball member 4 is fitted to the centre of a diffusing device, movement of the ball member will only control the volume and direction of the stream issuing from the centre, and, therefore, to shut off the whole device, two suitable lids 20 or covers 23 and 23¹ are arranged at the back of the diffuser and are mounted upon hinges 24 and 24¹. The lids are provided with upstanding members 25 and 25¹, to which a link 26 is pivotally connected by suitable pins or bolts, so that 25 the two ends move together. The hinge 24¹ is provided with an extension lever or the like 27, which is adapted to be engaged by means of a suitable cam 28 which may be operated from the front of the diffuser, by means of a knob 29 so 30 that when this is turned around the lid or the like will be swung about its hinge and removed from the diffuser, thereby letting air pass therethrough. When the cam is turned in the opposite direction, the lid will again fall by gravity 35 upon its seat. If desired, the lid may be restored to its initial closed position by spring means. If desired, wire mesh 30 may be placed over the back of the whole device below the lids 23 and 23¹.

40 The socket cover or locating plate may be fixed, if desired and the socket may be made removable. Further, instead of the socket, shown in Figures 1 and 7, having a number of ribs it may be made from a perforated plate of wire mesh or the like, 45 which is pressed or otherwise shaped hemispherically. When employed with a diffuser the flanges of the socket are extended so as to provide a vermin-proof protection over the whole opening.

It is to be understood that the apertures may 50 be made of any shape and size to suit requirements, and that instead of the two apertures being contained wholly within one hemisphere, they may project a small amount into the other hemisphere, as long as they are contained within 55 the socket or mounting in order to shut off the air completely.

The sphere may be made of any suitable material and may either be moulded or formed by other suitable means, with the desired apertures 60 and passage or slot, as the case may be, which may be of other shapes or forms than those described.

Further, it is to be understood that the controlling means may be fitted to any suitable air 65 duct or diffuser, and may be used in any ship, cabin, room or the like, whereby air is supplied to the apartment for ventilating, heating or cooling purposes.

I claim:

70 1. A ventilator comprising, a spherical member having an elbow air passage extending therethrough and terminating at the periphery thereof, a socket having an opening therein adjustably supporting said member so that air can be dis-

charged from an outlet end of the elbow passage in variable direction while an inlet end of the passage remains unobstructed by the socket, a spherical segment of said member having a diameter at least equal to the smallest diameter of the socket on the outlet side thereof and the two extremities of the air passage terminating outside said spherical segment, and the peripheral surface area of said segment extending over such a portion of the spherical member that the shortest chord defining the smallest limits of the segment is substantially equal to the diameter of the opening in the socket, whereby the passage of air through the ventilator can be cut off by turning the member to such position that said spherical segment closes the opening in the socket.

2. A ventilator comprising, a spherical member having an air passage extending therethrough and terminating at both ends at the periphery thereof, at least one baffle located within said passage to direct the stream of air passing therethrough, a socket having an opening therein in which said member is adjustably retained so that the air can be discharged from an outlet end of the passage in variable direction while an inlet end of the passage remains unobstructed by the socket, a spherical segment of said member having a diameter at least equal to the smallest diameter of the socket on the outlet side thereof and the two extremities of the air passage terminating outside said spherical segment, and the peripheral surface area of said segment extending over such a portion of the spherical member that the shortest chord defining the smallest limits of the segment is substantially equal to the diameter of the opening in the socket, whereby the passage of air through the ventilator can be cut off by turning the member to such position that said spherical segment closes the opening in the socket.

3. A ventilator comprising, a spherical member having an air passage extending therethrough and terminating at both ends at the periphery thereof, a socket having an opening therein, means movably mounted on the socket having

bearings supporting said member so as to be turned on an axis extending diametrically of said socket, said means being guided by the socket so that the bearings can be moved in the plane of said socket whereby the air can be discharged from an outlet in a variable direction while an inlet end of the passage always remains unobstructed by the socket, a spherical segment of said member having a diameter at least equal to the smallest diameter of the socket on the outlet side thereof and the ends of the air passage terminating outside said spherical segment, and the length of the arc of the segment measured in a plane at right angles to the axis of the bearings being equal to at least one-half of the circumference of the spherical member, whereby the passage of air through the ventilator can be cut off by turning the member about the axis of said bearings to such position that the spherical segment closes the opening in the socket.

4. A ventilator comprising, an air diffuser formed of vanes, a socket at the center of the vanes having an opening therein, a spherical member supported by the socket and having an angular air passage therethrough terminating at the periphery of said member, said spherical member being adjustable within the socket so that the air passing through the passage can be discharged in various directions while an inlet to the passage remains unobstructed by the socket, a spherical segment of said member having a diameter at least equal to the smallest diameter of the socket on the outlet side thereof and the two extremities of the air passage terminating outside the said spherical segment, and the peripheral surface area of said segment extending over such a portion of the spherical member that the shortest chord defining the smallest limits of the segment is substantially equal to the diameter of the opening in the socket, whereby the passage of air through the ventilator can be cut off by turning the member to such position that said spherical segment closes the opening in the socket.

NORMAN FINLAY JOHNSTON.
